UNITED STATES PATENT OFFICE.

WINTHROP L. JACOBS, OF EAST ORANGE, NEW JERSEY, ASSIGNOR TO THE
HARTFORD CARPET COMPANY, OF HARTFORD, CONNECTICUT.

DESIGN FOR A CARPET.

SPECIFICATION forming part of Design No. 14,877, dated March 11, 1884.

Application filed January 28, 1884. Term of patent 34 years.

To all whom it may concern:

Be it known that I, W. L. JACOBS, of East Orange, in the State of New Jersey, have invented a new and original Design for Carpets, 5 of which the following is a specification, reference being had to the accompanying photograph, which forms a part of the same.

This invention relates to a design to be worked into or upon surfaces, such as carpets 10 or similar fabrics; and it consists in the novel configuration and grouping of figures herein specifically shown and claimed.

The accompanying photograph is a face view 15 of a carpet showing my new design.

The design consists of a regular arrangement

of large conventional fan-like and otherwise shaped figures, as shown in the photograph, without conspicuous stem-connections. The space between these larger figures is closely filled in with angular right-lined shadow-work, 20 and with small gem figures and conventionalized leaf forms.

I claim—

The design for a carpet, substantially as shown and described.

W. L. JACOBS.
